Mark A. Kent ATTORNEY

UNITED STATES PATENT OFFICE

SIMON COOPER, OF BROOKLYN, NEW YORK, ASSIGNOR TO THE COOPER TEA PACKET CO., INC., OF BROOKLYN, NEW YORK, A CORPORATION OF NEW YORK

TAG WITH ATTACHED STRING AND METHOD OF ATTACHING

Application filed October 2, 1929. Serial No. 396,643.

This invention relates to fastening a tag to a string. It is particularly applicable to tags for individual tea bags but may be used for other purposes.

Individual tea bags are well known in the art. They consist essentially of a small fabric bag (containing an individual portion of tea leaves) which may be suspended in a teacup by means of a length of string which has one end attached to the bag and the other end attached to a tag. In packing these bags for sale a number of the bags are loosely thrown together in a box or carton, and the tags tangle up with the lengths of string, thus annoying the consumer when he attempts to withdraw one bag from the box.

Each tea bag is used only once and is then thrown away. Accordingly, it is very important from a commercial standpoint that the bags may be rapidly manufactured at very low cost. A considerable item of manufacturing expense is in attaching the tags to the lengths of string; and with this class of commercial articles, the minimizing of every phase of manufacturing cost is of the greatest importance.

An object of the present invention is to provide a fastening between a tag and length of string which will obviate tangling of the tags with the lengths of string when a number of the tags with strings attached are thrown together.

Another object of the invention is to provide a tag with attached string and/or method of attaching the tag to the string which enables the fastening to be rapidly accomplished at very small cost.

Another object of the invention is to provide a tag and string assembly and/or method of making the same which permits the use of relatively low grade stock for the tag.

Fig. 1 of the drawings is a side view of the tag with the string in place preparatory to being attached to the tag.

Fig. 2 is an edge view of the tag in the condition shown in Fig. 1.

Fig. 3 is a side view of the tag showing the completed assembly of tag and string.

Fig. 4 is an edge view of the tag in the condition shown in Fig. 3.

Fig. 5 is a reverse side view of the tag in the condition shown in Fig. 3.

Fig. 6 is a fragmentary sectional view 55 showing the tag attached to the string.

Fig. 7 is a fragmentary sectional view similar to Fig. 6, but showing a slightly modified form of the invention.

Fig. 8 is a plan view of a strip of metal 60 which is to be formed into a clamp for clamping the string to the tag.

Fig. 9 is an edge view of the finished clamp per se.

Fig. 10 is a perspective view of the finished clamp per se. 65

A tag 1 is pierced at 2 by a punch or piercing tool which introduces the end portion 3 of a piece of string 4 through the tag as shown in Fig. 1. A relatively thin strip of sheet metal 5 (shown in Fig. 8) is fed through the slot 2 in the tag, preferably by its pointed end 6. The strip of metal 5 is initially so placed through the slot 2 as to be beneath the string, and the strip is then bent into U-shaped form 75 as shown in Fig. 6 so as to embrace the end portion of the string and clamp it against both faces of the tag. Preferably, the ends of the strip 5 are driven into the surfaces of the tag as shown in Fig. 6, so as to eliminate 80 any crevices in which strings might catch when the tea bags are thrown together in packing.

In the alternative form shown in Fig. 7, the strip of metal 5 is made of such length 85 that, when bent into U-shaped form, the ends of the strip will project slightly beyond the edge of the tag. These projecting ends are clinched over the edge of the tag as shown in Fig. 7. This form of the invention provides an unusually secure anchorage for the string, and leaves no crevices or the like 90 which would cause tangling.

In making the tag assembly, string 4 may be drawn from a ball or reel and cut off in appropriate lengths. Similarly, the metal strips 5 may be cut from a continuous strip of sheet metal. The invention provides a construction (particularly in Fig. 7) in which the string extends directly away 100

from the tag and is a continuation of the edge of the tag. With the constructions used heretofore, the string has left the tag in such manner as to leave a V-shaped space 5 in which other pieces of string freely catch when the tea bags are thrown together in packing.

The string may be so arranged that the tip of it extends little or no distance beyond 10 the metal clamp 5, thus eliminating the usual frayed end which is unattractive and contributes to tangling of the tags. The U-shaped clamp embraces such a large surface of the tag that a low quality of tag stock can be used 15 without danger of the tag being torn from the string. The clamp 5 is preferably made of metal which can be readily bent to form and which does not easily rust or corrode. Aluminum and tin plate may be used for this 20 purpose.

It is realized that the present invention may be embodied in forms other than those particularly disclosed, and hence the present disclosure is to be considered as illustrative 25 in compliance with the patent laws, and is not to be considered as limiting.

What I claim is:

1. The method of fastening a tag to a string which comprises passing the string 30 and a sheet metal strip through the tag and clamping the string against both sides of the tag by bending the strip into U-shaped form.

2. The method of fastening a tag to a string which comprises punching a hole in 35 the tag and carrying the end of the string through the punched hole, passing a sheet metal strip through the hole, and then clamping the string against both sides of the tag by bending the strip into U-shaped form.

3. The method of fastening a string to a tag which comprises passing the string and a metal strip through the tag adjacent an 45 edge of the tag, bending the strip into U-shaped form to clamp the string against the faces of the tag, and clinching the ends of the strip over the edge of the tag.

4. In combination, a tag, a string lying against one face of the tag and having its 50 end portion passing through the tag and doubled back against the opposite face of the tag, and means passing through the tag and clamping the string against both faces of the tag.

5. In combination; a tag having a perforation adjacent its edge; a string having its end portion extending from the edge of the tag, through said perforation, and back toward the edge of the tag; and a U-shaped 60 clamp passing through the perforation and clamping the string against both faces of the tag, said clamp having at least one end clinched over the edge of the tag.

6. In combination; a tag having a slot-shaped perforation adjacent its edge; a U-

shaped strip of metal extending from adjacent the edge of the tag, through the perforation, and back to adjacent the edge of the tag on the opposite side; and a string having its end portion bent into U-shaped form, said end portion extending through the perforation and being clamped against the faces of the tag by said metal strip.

In testimony whereof I affix my signature.

SIMON COOPER.
